UNITED STATES PATENT OFFICE.

HARRY E. DOERR, OF ST. LOUIS, MISSOURI, ASSIGNOR TO SCULLIN-GALLAGHER IRON & STEEL COMPANY, OF ST. LOUIS, MISSOURI, A CORPORATION OF MISSOURI.

CAR-TRUCK.

1,077,969.

Specification of Letters Patent. Patented May 26, 1914.

Application filed December 26, 1913. Serial No. 808,828.

To all whom it may concern:

Be it known that I, HARRY E. DOERR, a citizen of the United States, residing at St. Louis, Missouri, have invented a certain new

5 and useful Improvement in Car-Trucks, of which the following is a full, clear, and exact description, such as will enable others skilled in the art to which it appertains to make and use the same.

10 This invention relates to car trucks, and more particularly to the means used in car trucks of the cast metal type for securing the spring plank and spring seat to the side frames.

15 The general practice in building car trucks of the type referred to is to connect the spring plank to the side frames by means of a plurality of rivets. In order to remove the bolster from the truck, it is necessary to first remove the spring plank, so that the bolster may be dropped down sufficiently low to permit of its withdrawal through the usual enlarged lower portion of the bolster-receiving opening. Consequently, a great amount of time and labor is expended in cutting or shearing off the rivet-heads that connect the spring plank to the side frames whenever the bolster of the truck has to be removed. The spring seats 20 in trucks of this type are usually formed of wood and rest directly on the spring plank in the bolster-receiving opening, and consequently must be recessed or cut out at numerous places in the bottom face thereof, so as to clear the rounded rivet-heads that connect the spring plank to the side frames, in order to have a perfectly flat bearing on the spring plank.

25 The main object of my invention is to provide a car truck of the type referred to in which the spring plank is connected to the side frames without the aid of rivets or similar fastening devices, thereby enabling it to be readily removed therefrom, whenever it is desired to remove the bolster or dismantle the truck, without having to cut off or drive out any fastening devices.

30 Another object is to provide a car truck of the class described in which the spring seats are provided with only one cut-out portion in their lower faces, instead of the numerous cut-out portions that have heretofore been necessary, in order to clear the usual fastening devices.

35 Another object is to provide a car truck

of the class described in which the first cost and the cost of maintenance thereafter is lower than in the trucks now in general use.

Other objects and desirable features will be hereinafter pointed out.

Figure 1 of the drawings is a side elevational view, partly in vertical section, of a portion of a car truck constructed in accordance with my invention; Fig. 2 is a horizontal sectional view taken on the line 2—2 of Fig. 1; and Fig. 3 is a vertical sectional view taken on the line 3—3 of Fig. 1.

Referring to the drawings which illustrate the preferred form of my invention, A designates a cast metal side frame that is provided with a bolster-receiving opening 1, in which are arranged the bolster 2, bolster-supporting springs 3, spring-seat 4, and the spring-plank 5. The bolster 2 may be of any approved construction and is provided with the usual column guides 6 that coöperate with the side walls or columns 7 in the upper portion of the opening 1, and the lower portion of said opening is slightly enlarged, the width of this portion being slightly greater than the width of the bolster through the column-guides 6; so that, in assembling the truck the bolster may be inserted through this enlarged portion and then raised upwardly until it lies between the columns 7, the spring-plank, spring-seat, and supporting springs being thereafter placed in position, as shown in Fig. 1. Co-operating means on the side frame and on the spring-plank are provided for maintaining said parts in operative position, said means consisting of a projection on one of said parts that coöperates with a recess on the other of said parts. In the embodiment of my invention, herein shown, this means

40 consists of a boss or projection 8, arranged in the bottom of the opening 1 of each of the side frames, and a coöoperating recess or perforation 9, formed in the spring-plank, adjacent each end thereof. The projections 8 are preferably non-circular or elongated in plan view, as shown clearly in Fig. 2, so as to overcome any tendency of the spring-plank to twist with respect to the side frame; and a bead or flange 9^a is preferably 45 pressed or struck up from the spring-plank around the margins of the perforation 9 so as to strengthen and reinforce the spring-plank at this point.

40 Another object is to provide a car truck

45 of the class described in which the first cost and the cost of maintenance thereafter is lower than in the trucks now in general use.

50 Another object is to provide a car truck of the class described in which the spring seats are provided with only one cut-out portion in their lower faces, instead of the numerous cut-out portions that have heretofore been necessary, in order to clear the usual fastening devices.

55 Another object is to provide a car truck

side with a cut-out portion or recess 10 that fits over the projection 8 and surrounding flange 9^a, in order that said spring-seat may rest or bear firmly on the spring-plank 4.

5 While I have herein described the spring-seat as being formed of wood and provided with a recess in the under side thereof, I do not wish to limit myself to such a construction, as said spring-seat could be 10 formed of metal, or the cut-out portion could extend entirely therethrough, without departing from the spirit of my invention.

Having thus described my invention, what I claim as new and desire to secure by Letters Patent is:

1. In a car truck, a pair of side frames, each of which is provided with a projection in the lower portion thereof, a pressed metal spring-plank provided adjacent each end 20 with a perforation that co-operates with said projection, and a flange surrounding the marginal edges of said perforation.
2. In a car truck, a pair of side frames, each of which is provided with a projection in the lower portion thereof, a pressed metal spring-plank provided adjacent each end 25 with a perforation that co-operates with said projection, a flange surrounding the mar-

ginal edges of said perforation, and a spring-seat that rests on said spring-plank 30 and is provided with a recess that receives said projection and flange.

3. In a car truck, a side frame provided with a bolster receiving opening, a projection arranged in the lower portion of said 35 opening, a spring-plank provided with a recess that co-operates with said projection, a projection on said spring-plank, and a spring-seat provided with a recess that co-operates with said last-named projection. 40

4. In a car truck, a side-frame provided with a bolster-receiving opening, a projection arranged in the lower portion of said opening, a spring-plank provided with an opening that co-operates with said projection, a marginal flange on said spring-plank that surrounds said opening, and a spring-seat provided with a recess into which said flange projects. 45

In testimony whereof I hereunto affix my signature in the presence of two witnesses, this 22nd day of December 1913.

HARRY E. DOERR.
